(57) **CLAIM**

The ornamental design for a chair pad, as shown and described.

DESCRIPTION

FIG. 1 is a front perspective view of a chair pad showing my new design;

FIG. 2 is a front view of the chair pad;

FIG. 3 is a rear view of the chair pad;

FIG. 4 is a right side view of the chair pad;

FIG. 5 is a left side view of the chair pad;

FIG. 6 is a top view of the chair pad; and,

FIG. 7 is a bottom view of the chair pad.

The broken lines illustrate portions of the chair pad that form no part of the claimed design.
